UNITED STATES PATENT OFFICE.

GEORGE A. WEBER, OF NEW YORK, N. Y., ASSIGNOR TO WEBER RAILWAY JOINT MANUFACTURING COMPANY, OF NEW YORK, N. Y., A CORPORATION OF WEST VIRGINIA.

STEP-JOINT.

SPECIFICATION forming part of Letters Patent No. 745,303, dated November 24, 1903.

Original application filed April 25, 1903, Serial No. 154,220. Divided and this application filed September 1, 1903. Serial No. 171,564. (No model.)

To all whom it may concern:

Be it known that I, GEORGE A. WEBER, a citizen of the United States, and a resident of the borough of Manhattan, city, county, and State of New York, have invented certain new and useful Improvements in Step-Joints, of which the following is a specification, accompanied by drawings.

This invention relates to railroad - rail joints, but more particularly to that class known as "step-joints;" and the objects of the invention are to improve upon the construction of such joints and increase their efficiency and strength, while at the same time simplifying their construction.

Further objects of the invention will hereinafter appear; and to these ends the invention consists of apparatus embodying the features of construction, combinations of elements, and arrangement of parts, substantially as hereinafter fully described and claimed in this specification and shown in the accompanying drawings, in which—

Figure 1 is a side view of a rail-joint embodying the invention. Fig. 2 is a plan view of the same, showing a plurality of filling-blocks adjacent the rails and extending along the same. Fig. 3 is a transverse sectional view of the joint. Fig. 4 is a plan view of a joint having continuous filling-blocks at each side of the rails.

This application is a division of my United States Patent No. 739,468, granted September 22, 1903, for improvements in step-joints; and the invention embodies filling-blocks at each side of the webs of the rails, with a continuous strap or band extending across the joint on the inside outside of the filling-blocks and opposing the bolt-plate, which may consist of the upright of the angle-chair.

Referring to the drawings, A represents a rail-chair having a base B and an upright or bolt plate C, with a longitudinally-extending strengthening rib or fillet at the juncture of the base and upright. The meeting ends of the rails E and F are supported upon the base of the rail-chair or angle-plate. In this instance the rail E is taller and heavier than

the rail F, and means are provided for maintaining the rails in surface and alinement. 50 The base B of the chair is stepped to bring the rail F of lesser height into surface with the rail E. In this instance transverse cleats G are shown, upon which the rail F rests. These cleats may be secured by rivets H to 55 the base B, although any other suitable means may be provided for forming the stepped portion upon the base of the chair, and I do not limit myself to cleats.

Extending along the webs of the rails are 60 shown filling-blocks, which are preferably of wood. In Fig. 2 the filling-blocks are in sections I J and K L, while in Fig. 4 they are shown as continuous blocks O P. Whether the blocks are made sectional or continuous, 65 they are so constructed and fitted between the heads and bases of the rails that they maintain the rails in surface and alinement.

Extending along the filling block or blocks on the inside of the joint and opposite the 70 bolt-plate C is a continuous strengthening band or strap Q, extending across the joint. The band or strap Q, which is a metallic bar, opposes the bolt-plate C, and suitable bolts R extend through the parts of the joint and hold said parts firmly together. When the bolts are tightened, a strong and efficient joint is obtained, the filling-blocks being tightly clamped between the bolt-plate C and the opposing member or bar Q. 75

Obviously the construction may be varied without departing from the spirit of the invention, and therefore without limiting myself to the construction shown and described

I claim, and desire to obtain by Letters Patent, 85 the following:

1. A rail-joint, comprising an angle-chair having a base and an upright, rails of different weight and height supported in surface upon said chair, filling-blocks at one side of 90 the joint extending along the webs of the rails, filling-blocks at the other side of the webs of the rails between the rails and the upright of the chair, said blocks being constructed to maintain the rails in surface and alinement, 95 a strap or band extending across the joint

- outside of the filling-blocks and opposing the upright of the angle-chair, and bolts for securing the parts of the joint together, for substantially the purposes set forth.
5. 2. A rail-joint, comprising a rail-support affording provision for supporting rails of different weight and height in surface, filling-blocks at each side of the joint extending along the webs of the rails, a bolt-plate and an opposing strap or band, the filling-blocks being constructed to maintain the rails in surface and alinement, and bolts for securing the parts of the joint together, for substantially the purposes set forth.
15. 3. A rail-joint, comprising means for supporting rails of different weight and height in surface, sectional filling-blocks at each side of the webs of the rails, a bolt-plate and an opposing strap or band at the other side of the joint, the filling-blocks being constructed to maintain the rails in surface and alinement, and bolts for securing the parts of the joint together, for substantially the purposes set forth.
4. A rail-joint, comprising a base-plate affording provision for supporting rails of different weight and height in surface, two wooden filling-blocks at each side of the webs of the rails, said blocks being constructed to maintain the rails in surface and alinement, a bolt-plate and an opposing strap or band, and bolts for securing the parts of the joint together, for substantially the purposes set forth.
5. A rail-joint, comprising a stepped base-plate, rails supported thereon, filling-blocks at each side of the webs of the rails, a bolt-plate and an opposing strap or band, and bolts for securing the parts of the joint together, for substantially the purposes set forth.

In testimony whereof I have signed this specification in the presence of two subscribing witnesses.

GEORGE A. WEBER.
